UNITED STATES PATENT OFFICE.

WILLBURN C. GRANT, OF ABILENE, TEXAS.

ICE-MACHINE.

1,344,502.

Specification of Letters Patent. Patented June 22, 1920.

Application filed June 10 1919. Serial No. 303,159.

To all whom it may concern:

Be it known that I, WILLBURN C. GRANT, a citizen of the United States, residing at Abilene, in the county of Taylor and State of Texas, have invented a new and useful Ice-Machine, of which the following is a specification.

This invention relates to machines for manufacturing ice.

10 One of the objects of the invention is to combine with the refrigerating apparatus a means whereby the water used for cooling the jackets of the compressor is also used to spray over the ammonia condensing coil of 15 the apparatus after which the water is collected and again directed into the jacket of the compressor.

20 A further object is to provide means whereby a forced circulation of the water is set up, the pump used for this purpose operated with another pump employed for producing a circulation of the brine in the freezing tank.

25 With the foregoing and other objects in view, which will appear as the description proceeds, the invention resides in the combination and arrangement of parts and in the details of construction hereinafter described and claimed, it being understood that, within 30 the scope of what is claimed, changes in the precise embodiment of the invention shown can be made without departing from the spirit of the invention.

35 In the accompanying drawing, which is a diagrammatic view partly in plan and partly in elevation of the apparatus constituting the present invention, the preferred form of the invention has been shown. The tank, engine and compressor are shown in 40 plan while the condensing coils and water collecting tank 31 are shown in elevation.

45 Referring to the drawings by characters of reference 1 designates a brine tank in which are arranged cans 2 having central tubular cores 3. An ammonia coil 4 is arranged within the tank and around the cans and then communicates through a pipe 5, with an ammonia tank 6. The other end of the coil 4 is connected by a pipe 7 with the 50 inlet port of a compressor 8. An ammonia condensing coil 9 is connected at its lower end by a pipe 10 to the ammonia tank 6 while its other end is connected by a pipe 11 to the compressor 8.

Arranged adjacent the brine tank is a 55 pump cylinder 12 in which is located a piston 13 connected to a rod 14 which extends entirely through the cylinder and is suitably guided, a pitman 15 connects the rod to an eccentric 16 so that during the rotation 60 of the shaft 17 the said piston will be reciprocated. Said shaft 17 is adapted to be driven by any suitable mechanism such as a belt mounted on a pulley 18 and a pitman 19 may be employed for transmitting motion 65 from a crank 20 to the compressor 8 as will be obvious.

A pipe 21 extends from the cylinder 12 and into the brine tank 1 and a return pipe 22 is arranged in the bottom portion of the 70 brine tank and has branch pipes 23 provided with upwardly extending nozzles 24 located in the cores 3. Valves may be suitably arranged so that, when the piston 13 is reciprocated, circulation of brine will be set up in 75 the tank, some of the brine being sucked through the nozzles 24 and the pipes 23 to the pipe 22 and thence to pipe 21 from which it will be discharged back into the tank, thus completing the circulation of brine. 80

Another pump cylinder 25 is arranged in line with the cylinder 12 and has a piston 26 therein connected to and movable with the rod 14. An outlet pipe 27 extends from the cylinder 25 to a spray pipe 28 arranged above the coil 9 and this outlet pipe may be provided with a check valve 29 to prevent return flow of water within the pipe. A pan 30 is arranged under the coil for collecting the water after it has gravitated over the 90 coil 9 and this pan opens downwardly into a tank 31 from which a pipe 32 extends to the water jacket of the condenser 8. Another pipe 33 extends from said water jacket to the cylinder 25 and may be provided with 95 a check valve 34 to prevent flow of water from the cylinder 25 back to the water jacket.

From the foregoing it will be apparent that during the operation of the compressor 100 the piston 26 will be reciprocated and will set up a circulation of water, said water being sucked out of the water jacket of the compressor 8 and forced through the pipe 27 to the spray pipe 28. From this pipe the 105 water will fall onto the coil 9 and trickle down to the pan 30. From this pan it will enter the tank 31 and will return, by way of

the pipe 32, to the water jacket 8. Thus the same water used for spraying the coil 9 is used for cooling the compressor.

What is claimed is:

- 5 In an apparatus of the class described the combination with an ammonia condensing coil, and a compressor provided with a water jacket, of a water tank in communication with said jacket, a pan for collecting
- 10 water from under the ammonia condensing coil and directing it to the tank, a pump, a

pipe connection between the water jacket and the pump, a spray pipe extending over the ammonia condensing coil and a pipe connection between said spray pipe and pump. 15

In testimony that I claim the foregoing as my own, I have hereto affixed my signature in the presence of two witnesses.

WILLBURN C. GRANT.
